(57) **CLAIM**

The ornamental design for input device with trackball, as shown and described.

DESCRIPTION

FIG. 1 is a top, rear, and left side perspective view of our input device with trackball as shown and described; FIG. 2 is a top, front, and left side perspective view thereof; FIG. 3 is a top plan view thereof; FIG. 4 is a bottom plan view thereof; FIG. 5 is a front elevation view thereof; FIG. 6 is a rear elevation view thereof; FIG. 7 is a right side elevation view thereof; and, FIG. 8 is a left side elevation view thereof.

The broken lines shown to be immediately adjacent to the shaded/contoured areas represent certain portions of the bounds of the claimed design while all other broken lines are directed to environmental features and are provided for illustrative purposes only; the broken lines form no part of the claimed design.
